UNITED STATES PATENT OFFICE

2,007,457

MUD JACK SLEEVE FOR HIGHWAYS AND
THE LIKEEdward H. Peters, Chicago, Ill., assignor to James
H. Jacobson, Chicago, Ill.

Application November 29, 1933, Serial No. 700,218

10 Claims. (Cl. 94—39)

The invention relates to a thimble or sleeve adapted to be embedded in concrete or other material of which roadways, walks and the like are usually formed, and thereby provide a passage 5 through the pavement to form means of communication with the subgrade. Also to provide means through which a filler may be pumped or otherwise introduced between the under surface of the pavement and the surface of the subgrade to thus fill voids occurring in the subgrade and thereby prevent the lowering or settling of the pavement; and to provide means through 10 which a filler may be introduced under pressure to cause the pavement to be elevated should a portion thereof become dislocated relatively to the plane of the road.

Other objects of the invention are to provide a structure capable of forming a permanent part of the roadway; a structure which will withstand road load and the forces of nature as applied thereto; and, in addition, will provide a convenient means through which to inspect the subgrade; and will further provide means whereby the labor necessary in order to make such an 25 inspection is materially reduced.

A further object of the invention is to provide a construction which will prevent loosening of the sleeve when cast into the roadway, to further resist the pulsating action as applied thereto by the pump during the introduction of the filler to the subgrade; and, in addition, to withstand the resultant back-pressures as developed or as applied to said device.

It is still a further object of this invention to 35 provide a sleeve which is of a length corresponding approximately to the thickness of the roadway at the point of application of the sleeve to the roadway, which sleeve is adapted to be supported in a pre-determined position upon the subgrade whereby during the pouring operation it becomes properly embedded in the material of 40 the roadway, and thus provides a passage which extends through the pavement to establish communication with the subgrade.

It is also an object to provide a structure which is of a length substantially equal to the thickness of the roadway and which is securely cast into the roadway and retained against relative 45 displacement to the roadway, which in addition is provided with a closure which may be manipulated to permit inspection of the subgrade through the passage formed by the sleeve. The closure is employed to assist in sealing the sleeve against the introduction of water to the sub-

grade, and thus prevent the development of a void in the subgrade.

Another object of the invention is to provide one end of the sleeve with means whereby a hose end, hose nozzle, or other similar element may be separably connected with the sleeve.

In addition, it is an object to provide closures for the opposite ends of said sleeve to thus respectively prevent the infiltration of water, dirt, or ice through one end of the sleeve, and in addition prevent the surging of the filler from the subgrade into the interior of the sleeve, and provide means for removing excess mud from the interior of the sleeve to maintain it in a condition facilitating inspection of the subgrade.

The invention has these and other objects, all of which will be explained in detail and more readily understood when read in conjunction with accompanying drawings which show various structures which may be resorted to; it being, 20 therefore, obvious that changes and modifications may be made without departing from the spirit of the appended claims forming a part hereof.

In the drawings, Figure 1 is a plan view of the fragmentary portion of a sidewalk or roadway;

Fig. 2 is a sectional view of a fragment of a roadway showing the device as applied thereto and having a hose connected therewith whereby mud or some other filler is introduced to a void below the pavement;

Fig. 3 is a sectional view of the sleeve shown in Fig. 2;

Fig. 4 is a fragmentary sectional view of a modified structure;

Fig. 5 is a plan view of a fragment of a roadway showing a top view of the sleeve shown in Fig. 3;

Fig. 6 is a sectional view of a sleeve showing another arrangement which may be resorted to 40 showing the manner of supporting the sleeve prior to pouring of the roadway or pavement;

Fig. 7 is a sectional view of the structure shown in Fig. 6 illustrating a closure employed with the structure;

Fig. 8 is a sectional view taken on line 8—8 of Fig. 7;

Fig. 9 is a sectional view similar to Fig. 6 showing the application of a hose nozzle to the sleeve;

Fig. 10 is a detail side elevation of the closure shown on Fig. 7;

Fig. 11 is a side view of the structure shown in Fig. 10;

Fig. 12 is a sectional view taken on line 12—12 of Fig. 7;

Fig. 13 is a plan view of the structure shown in Fig. 10;

Fig. 14 is a sectional view of the upper end of the sleeve shown in Figs. 6 and 7;

5 Fig. 15 is a side elevation of the upper end of the sleeve shown in Figs. 6, 7, 9 and 14;

Fig. 16 is a fragmentary sectional view of the lower end of the sleeve showing same provided with a support for the sleeve, the support having means for the reception of stakes for holding the sleeve in position on the subgrade prior to pouring of the roadway; and

10 Fig. 17 is a fragmentary sectional view of a modified sealing means which may be employed in the structure.

The embodiment of the invention illustrated in Figs. 1 to 4 contemplates the provision of a tubular element or sleeve 10, which is embedded in the concrete forming the roadway 11; it being understood that the sleeve is supported by the subgrade 12 prior to pouring of the pavement; the sleeves being located at those points of the subgrade at which a void is liable to occur. The tubular element or sleeve 10 is formed with an enlargement 13 at its upper end, to thus form an outwardly extending shoulder 14, and an enlargement for the reception of the end of the nozzle secured to the hose 15, through which mud or some other suitable filler 16 is pumped to and through the sleeve, and thence to the void below the pavement.

The sleeve 10 is further provided with an externally arranged annular rib or extension 17, which also becomes embedded in the concrete of the roadway during the pouring operation and forms means to resist the loosening of the sleeve due to shrinkage of the concrete upon its initial set, and resist the force of the pulsating action produced by the operation of the pump whereby mud or filler 16 is forced under pressure into the void.

45 The pressure under which the material is fed to the void may in some instances be sufficient to cause a vibratory action to be applied to the sleeve which would tend to cause its becoming loosened from the concrete, but this difficulty is overcome by means of the annular rib and may be further insured against by means of a structure herein-after to be referred to.

50 The sleeve may be supported in any suitable manner relatively to the subgrade 12. The means shown in Fig. 3 contemplates providing a sleeve of a length slightly greater than the thickness of the roadway so that the top lies flush with the surface of the roadway with the end 18 embedded in the subgrade to thus support the sleeve during the pouring operation. It is understood that the invention is not limited to the arrangement shown in Fig. 3 as the sleeve may be supported in 55 a manner other than that contemplated by this structure.

The enlargement 13 of the sleeve is formed to receive the closure 19, which, in the embodiment of the invention illustrated in Fig. 3, is merely a plug which rests upon the internal shoulder 20, and will thus accept and transmit any load applied to the closure 19, to the shoulder 14, and thence to the roadway.

70 The upper end of the sleeve shown in Fig. 4 substantially corresponds to the upper end of the sleeve shown in Fig. 3, however, differs therefrom in that the internal portion of the upper end of the sleeve is threaded, as indicated at 21, to receive the threaded plug or closure 22. These 75 threads may also be employed to connect the

threaded end of a hose or hose coupling with the sleeve to thereby hold the hose against displacement during the pumping of the filler into the void.

5 In Figure 6 another structure for supporting the sleeve is illustrated. This structure contemplates the utilization of a tool having a shank or spindle 23 which is pointed at its lower end and has its upper end provided with a head 24, the head also including a reduced portion 25 10 which respectively cooperate with the recesses 26 and the internal surface of the tubular portion 27, extending below the recesses. An apertured disc 28 is mounted on the spindle or shank 23 and is adjustable along the spindle to thus compensate 15 for different lengths of sleeves.

A set screw 29 is employed to secure the disc 28 at various positions longitudinally of spindle 23. It is understood that the disc 28 is employed to support the lower end of the sleeve against lateral displacement and that this structure and the head 24 and portion 25 provides a construction which will support the sleeve in a vertical position during the pouring operation and which may be withdrawn from the sleeve after the concrete 25 has set.

The sleeve illustrated in Figures 6 and 7 is generally designated 10A and is provided with an annularly arranged flange 30 which functions in a manner similar to the flange 17. The sleeve 10A is further provided with a plurality of longitudinally extending ribs 31-31 which function to prevent rotation of the sleeve relative to the pavement.

30 By referring to Figures 8 and 14, it will be noted that the upper end of the sleeve 10A is provided with a plurality of bayonet slots 32-32 which function to removably lock the closure generally designated 33 within the sleeve.

35 The closure generally designated 33 is designed to provide a closure 34 for the upper end of the sleeve and the closure 35 for the lower end thereof, the closures being connected with each other through the agency of a webbed shank 36 which thus provides a unitary structure which may be 40 removably associated with the sleeve. The closure generally designated 33 is formed to provide the transversely arranged rib 37, the opposite ends of which terminate in projections or lugs 38-38 which respectively cooperate with the 50 bayonet slots 32 to rotatably and releasably lock the closure generally designated 33, relatively to the sleeve, and in addition function to assist in insuring a proper seal to be effected between the closure and the top of the tubular member. The 55 closure structure 33 is also designed to provide an annular shoulder 39, which is of a lesser diameter than closure 34 and thus provides a space for the reception of a washer or gasket 40. The shoulder 39 is adapted to engage the annular shoulder 41 of the sleeve and thus any road shock delivered to the closure 34 will be transmitted through the washer 40 to the shoulder of the sleeve.

60 It may be here stated that the washer may be of any suitable resilient material, either metal, rubber, or fibre, which may be compressed to form a water-tight seal. It will be noted that the bayonet slots 32 are slightly inclined so as to 65 provide a cam action to thereby lock the closure with the sleeve upon rotation of the closure and compress the seal or washer 40. Each of these bayonet slots is provided with a recess 42 for the reception of the repetitive lugs 38, which enter 75

these recesses 42 and lock the closure against accidental rotation and release from the sleeve.

By referring to Fig. 13 it will be noted that the cover is provided with indicia so that the user may be apprised of the direction of rotation in order to cause release or locking of the closure with the sleeve. The closure is provided with an opening 43 for the reception of a suitable tool for accomplishing rotation of the closure.

10 It may be here stated that the bayonet slots 32 perform a dual function in that they provide means for releasably locking the closure to the tubular member and in addition provide means for releasably locking a hose nozzle generally designated 44 with the sleeve when it is desired to introduce a filler to a void.

15 The nozzle 44 is provided with lugs 45, which are introduced through the throat of the bayonet slots and upon rotation of the nozzle will thus secure against accidental separation of the latter from the sleeve. It has been found that considerable pressure is exerted upon the sleeve and the nozzle during the pumping of the filler to the void, which tends to loosen the sleeve from the pavement. This last mentioned objection is obviated by means of the annular rib 30 and the vertical ribs 31.

20 It is also understood that the sleeve 30 may be of a length approximately equal to the thickness of the roadway and will thus differ from the structure shown in Fig. 3, which is a slightly greater length.

25 The sleeve 30 may be provided with a base or foot piece 46 which is of a sufficient diameter to support the sleeve in a vertical position relatively to the subgrade. This base may be provided with means for the reception of stakes 47 or other holding means which are driven into the subgrade through openings 48 provided in the base to thus hold the sleeve against displacement during the pouring of the roadway or pavement.

30 Fig. 17 illustrates a modified seal which may be employed at the juncture at closure 34 and the shoulder 41. This seal 49 may be of a tubular or circular cross section and will provide greater resiliency to the seal.

35 From the foregoing description of the invention, it is believed evident that a sleeve is provided which may be successfully supported by the subgrade during the pouring of the pavement or roadway and which has means for locking the sleeve in the roadway in a manner to prevent displacement thereof relatively thereto and thus compensate for the shrinkage of the material of the roadway or the occurrence of rust, either of which contingencies might cause the sleeve to become loosened so that it may be removed from the pavement.

40 It is further manifest that the structure provides means for sealing the opposite ends of the sleeve to thus respectively prevent the filler from surging from the void into the sleeve and the passage of water, etc. from the exterior of the roadway through the sleeve should the sleeve be located at the base of a hill or some other hollow where water is liable to congregate and temporarily lodge during a rain or thaw of a snowfall. This insures against the introduction of water to the subgrade which might initiate the formation of a void in the subgrade.

45 It is also believed evident that means are provided whereby a hose end or a hose nozzle may be separably locked to the sleeve to thus eliminate the necessity of manually holding the hose during the introduction of the filler to a void.

50 It is also believed manifest from the foregoing that the structure eliminates much of the manual labor now necessary in order to introduce filler to a void which introduction is now accomplished by drilling a hole through the pavement and after filling the void plugging the hole with pitch, tar, etc. which has to be removed from the passage should it be found that additional filler material is necessary in order to fill the void and produce a substantial support for an adjacent slab 5 section of the road.

55 The closure 35 performs the additional function of providing means for expelling excess mud from the interior of the sleeve which thereby maintains the interior of the sleeve free of excess mud and 10 in a condition which facilitates inspection of the subgrade through the thimble or sleeve.

60 Having thus described the invention, what I claim and desire to cover by Letters Patent is:—

1. A device of the kind described comprised of a tubular member one end of which provides a support whereby said tubular member may be supported by the subgrade of a roadway during pouring of pavement for said roadway to thereby embed said tubular member in said pavement, said tubular member being of a length approximately equal to the thickness of said pavement at application of said tubular member to the roadway and providing a passage for accomplishing communication with a portion adjacent the upper 30 surface of the subgrade, a closure for the upper end of said tubular member having means for releasably locking said closure to said end of said tubular member, and a closure for the lower end of said tubular member connected with said 35 first mentioned closure.

2. A device of the kind described comprised of a tubular member one end of which provides a support whereby said tubular member may be supported by the subgrade of a roadway during 40 pouring of pavement for said roadway to thereby embed said tubular member in said pavement, said tubular member being of a length approximately equal to the thickness of said pavement at application of said tubular member to the roadway and 45 providing a passage for accomplishing communication with a portion adjacent the upper portion of the subgrade, a closure for the upper end of said tubular member having means for separably connecting said closure with said tubular member, and a closure for the lower end of said tubular member connected with the closure for the upper end of said tubular member, said 50 closures being adapted to be inserted and withdrawn from said tubular member through the 55 upper end of said tubular member.

3. A device of the kind described comprised of a tubular member one end of which provides a support whereby said tubular member may be supported by the subgrade of a roadway during 60 pouring of pavement for said roadway to thereby embed said tubular member in said pavement, said tubular member being of a length approximately equal to the thickness of said pavement at application of said tubular member to the roadway and 65 providing a passage for accomplishing a communication with a portion of the subgrade adjacent the upper portion of the subgrade, a member the opposite ends of which respectively provide closures for the opposite ends of said 70 tubular member, and means for releasably locking said closures with respect to said tubular member.

4. A device of the kind described comprised of a tubular member one end of which provides a 75

- support whereby said tubular member may be supported by the subgrade of a roadway during pouring of pavement for said roadway to thereby embed said tubular member in said pavement, said tubular member being of a length approximately equal to the thickness of said pavement at application of said tubular member to the roadway and providing a passage for accomplishing a communication with a portion of the subgrade adjacent the upper surface of the subgrade, a member, the opposite ends of which respectively provide closures for the opposite ends of said tubular member, said closure for the upper end of said tubular member and said tubular member having elements which cooperate with each other to releasably lock said closures with respect to said tubular member.
5. A device of the kind described comprised of a tubular member one end of which provides a support whereby said tubular member may be supported by the subgrade of a roadway during pouring of the pavement for said roadway to thereby imbed said tubular member in said pavement, said tubular member being of a length approximately equal to the thickness of said pavement at application of said tubular member to the roadway and providing a passage for accomplishing communication with a portion adjacent the upper surface of the subgrade, a closure releasably associated with the upper end of said tubular member, means sealing the tubular member against the passage of water, through said member, said closure and tubular member having means cooperating with each other to releasably connect said closure and tubular member and effect said seal, said sealing means being located above said means for connecting said closure and tubular member.
6. A device of the kind described comprised of a tubular member one end of which provides a support whereby said tubular member may be supported by the subgrade of a roadway during pouring of the pavement for said roadway to thereby imbed said tubular member in said pavement, said tubular member being of a length approximately equal to the thickness of said pavement at application of said tubular member to the roadway and providing a passage for accomplishing communication with a portion adjacent the upper surface of the subgrade, a closure removably associated with the upper end of said tubular member, a member extending from said closure into said tubular member, to adjacent the opposite end of said tubular member and providing a closure for said last mentioned end of said tubular member and means provided between said closures providing an element of means for releasably locking said closures to said tubular member.
7. A device adapted to be imbedded in a pave-
- ment and provide for communication with the upper surface of the subgrade of said pavement, said device being comprised of a tubular member of a length substantially equal to the thickness of the pavement and having an enlargement providing an internal and external shoulder, the internal shoulder providing a seat limiting movement in one direction of a closure for said tubular member, said tubular member having an element of means for effecting a separable connection between said tubular element and closure.
8. For facilitating the pumping of filling material under the surface material of a highway, street, or the like, where filling below said surface material has been washed away or has sunken, or where the surface material has raised and it is desirable to fill the existing void, a pavement having anchored therein as a permanent part thereof a tubular member which passes through the pavement, and a member adapted to be removably mounted in said tubular member, said second mentioned member including a closure for the upper end of said tubular member having a plunger connected with the closure and having a part at its lower end closing the lower end of the tubular member and said part acting to force any material in the tubular member therefrom when the closure and plunger are arranged in the tubular member.
9. A device of the class described comprising a sleeve and a closure member therefor, said sleeve having an internal shoulder at its upper end, a closure member being removably mounted in said sleeve, said closure member being seated on the shoulder and having its upper face flush with the upper end of the sleeve, said sleeve and closure member each being provided with an element of a lock for releasably locking the closure to the sleeve, a plunger connected with the closure and extending through the sleeve with its lower end closing the lower end of the sleeve when the closure is in position in said sleeve.
10. A device of the class described comprising a sleeve having an internal shoulder at its upper end, a removable closure member adapted to be removably mounted in said sleeve and be seated on the shoulder and having its upper face flush with the upper end of the sleeve, a plunger connected with the closure and extending through the sleeve with its lower end closing the lower end of said sleeve when the closure is in position, means for holding the closure in closing position, said means including elements provided in the sleeve extending downward from the shoulder and means provided on the closure which cooperate with the elements of the sleeve, to separably lock the closure to said sleeve upon rotation of said closure.

EDWARD H. PETERS.
